UNITED STATES PATENT OFFICE.

JACOB P. WRIGHT, OF BARBERTON, AND CHARLES F. WRIGHT, OF AKRON, OHIO,
ASSIGNORS TO THE DIAMOND MATCH COMPANY, OF CHICAGO, ILLINOIS, A COR-
PORATION OF ILLINOIS.

CARRIER FOR CARD-MATCH MACHINES.

1,400,338.

Specification of Letters Patent.

Patented Dec. 13, 1921.

Application filed April 9, 1921. Serial No. 460,123.

To all whom it may concern:

Be it known that we, JACOB P. WRIGHT and CHARLES F. WRIGHT, citizens of the United States, and residents, respectively, of Barberton and Akron, both in the county of Summit and State of Ohio, have invented certain new and useful Improvements in Carriers for Card-Match Machines, of which the following is a specification.

This invention relates to carriers for machines for making card-matches, such, for example, as illustrated in Letters Patent of the United States No. 636,170, dated October 31, 1899.

The object of our invention is to provide a card-match carrier whereof the individual link members possess great strength and relative lightness; whereby the rigidity and parallelism of the card-clamping devices of adjoining links is preserved, and whereby provision is had for the accurate setting of the leading end of the match stock in the carrier, all as will be hereinafter described and claimed.

In the drawings

Figure 1 is a back view of a match-card carrier link embodying my invention.

Fig. 2 is a front view of the same.

Fig. 3 is a longitudinal vertical section of the link, on the line 3—3 of Fig. 2.

Fig. 4 is a transverse section, enlarged, on the line 4—4 of Fig. 2, showing adjoining ends of adjacent links.

Referring to the drawings, 10 designates one of the link or plate members of an endless carrier for holding the marginal portions of match cards and transporting the cards in spaced relation to each other throughout the match-making path. The body of each link is preferably an integral metal structure comprising two end portions 11 rigidly connected by spaced parallel bars, to wit, a central bar 12, two side bars 13, and two bars 14 intermediate the central bar and the respective side bars 13. The rear of the central bar is connected midway between its ends to the adjacent bars 14 by right-angle extensions 15, the space between which latter and the adjacent side bars 13 being open and unobstructed, as indicated at 16. The bars 12 and 14 being relatively wide are preferably longitudinally channeled for lightness. Each end portion 11 of the plate is provided with suitable ears 17 whereby adjoin-

ing plates can be hingedly jointed, and also with rack-teeth 18 which are designed to mesh with the usual gear wheels that transmit motion to the carrier.

Secured to the forward or outer faces of the bars 14 are U-shaped spring clamps 19, the limbs of which straddle such bars and bear yieldingly against the adjacent sides of the central bar 12 and the respective side bars 13 in such a manner that the edge of the match card stock can be readily inserted between the clamps and the opposing inner wall of a bar 12 or 13. In the present instance two spring clamps are mounted on each bar 14, the limbs of which clamps and the opposing walls of the bars 12, 13 have coinciding semi-circular recesses 20, 21 respectively, which provide openings for the passage of the usual reciprocating punches by means of which the completed match cards are ejected from the carrier.

The outer faces of the side bars 13 of each plate are provided with a series of spaced convex lugs 22, which are so formed and disposed that when the plates are hinged together, the lugs of one plate bear against those of the adjoining plate and thus afford between the adjacent side bars of the plates a rocking support which braces and reinforces the bars while the leading edge of the match-card stock is being entered in the clamps, thus preserving the parallelism of the side bars notwithstanding the absence of the median supporting connection at 16, and also permitting the flexing of the carrier as it progresses about the usual guide wheels of the match machine.

Preparatory to the operation of the machine the unobstructed clamping space between the side bars 13 and the intermediate bars permits the irregular end of a roll of stock to be pushed entirely through such space and then pulled sufficiently rearward of the plate to position the stock in accurate register with the transverse card cutting knife which is attached to the usual splint punching head. Thus the bad end of the stock can be initially cut off and then manually pulled through and out of the plate. This being done the "trued" end of the paper when the machine is started is advanced to and inserted in the carrier by the usual rolls, and the match card is severed from the stock, such stock being intermittently ad-

vanced to each succeeding clamping space of the carrier and subjected to the action of the splint punching and card cutting devices in the usual manner.

5 We claim—

1. A match-card carrier embodying hingedly-connected link members, whereof each member comprises toothed end portions having joint connections, spaced apart 10 side bars connecting such portions, spring clamps arranged to bear against the inner faces of said bars, and rocker-lugs on the outer faces of the bars, said lugs being so disposed that those of adjoining link members 15 contact with each other.

2. A match-card carrier embodying hingedly-connected link members, whereof each member comprises toothed end portions, a central bar, two side bars and two 20 bars intermediate the central bar and the respective side bars, all said bars being in spaced parallel relation to each other and connecting said end portions, said central bar having angular extensions connecting

the said intermediate bars, and U-shaped 25 spring clamps fastened to and straddling intermediate bars.

3. A match-card carrier embodying hingedly-connected link members, whereof each member comprises toothed end portions, a central bar, two side bars and two 30 bars intermediate the central bar and the respective side bars, all said bars being in spaced parallel relation to each other and connecting said end portions, said central 35 bar having angular extensions connecting the said intermediate bars, rocker-lugs on the outer faces of the side bars so disposed that the lugs of adjoining link members contact with each other, and U-shaped spring clamps 40 fastened to and straddling intermediate bars.

Signed at Barberton, in the county of Summit and State of Ohio, this 7th day of April, A. D. 1921.

JACOB P. WRIGHT.
CHARLES F. WRIGHT.
